S.E. Tompkins,
Hooks & Terrets for Harness Saddles,
No. 36,248, Patented Aug. 19, 1862

Alawley

Inventor
Sam'l S. Tompkins

UNITED STATES PATENT OFFICE.

SAMUEL E. TOMPKINS, OF NEWARK, NEW JERSEY.

IMPROVEMENT IN HOOKS AND TERRETS FOR HARNESS-SADDLES.

Specification forming part of Letters Patent No. 36,248, dated August 19, 1862.

To all whom it may concern:

Be it known that I, SAMUEL E. TOMPKINS, of Newark, in the county of Essex and State of New Jersey, have invented a new and useful Improvement in the Construction of Hooks and Terrets for Harness-Saddles; and I do hereby declare that the following is a full, clear, and exact description of the same, reference being had to the accompanying drawings, making a part of this specification, in which—

Figure 1 is a side view of a hook constructed according to my invention. Fig. 2 is a side view of the metal frame of the same. Fig. 3 is a side view of a hook partially constructed. Fig. 4 is a section of Fig. 1, taken in the line $\alpha\alpha$. Fig. 5 is a side view of a hook as ordinarily constructed, drawn with a view of showing the difference between it and my invention.

Similar letters of reference indicate corresponding parts in the several figures.

This invention relates to an improvement in the construction of that kind of saddle hooks and terrets which are covered with leather and provided with a metal lining to prevent the wearing of the leather under the friction of the reins and strap.

The object of the invention is to obtain a neater and more durable hook and terret than those constructed in the ordinary way, and also a more economical mode of manufacture, which will not only admit of the hooks and terrets being repaired with facility when worn or soiled by use, but which will also admit, when desired, of genuine silver plate being used as a lining, the old mode of construction being confined to German-silver lining for the best class of work. To effect these results my invention consists in constructing the metal frame or body of the hook and terret of two parts, arranged in such a manner that it will form what may be termed a "clamp," to hold the leather covering which incloses the outer or exterior part of the frame only, while the inner part is made to serve the purpose of a metal lining, the whole in general appearance resembling the ordinary hook and terret, but being much neater in detail and more durable, for reasons hereinafter fully set forth.

To enable those skilled in the art to fully understand and construct my invention, I will proceed to describe it.

A, Fig. 2, represents the frame or body of a

hook, which is of metal and composed of two parts, a b . The inner part, a , has a flat plate or shank, c , at its lower end, through which the screw B passes that secures the hook to the saddle, and the upper part has a conical terminal or tip, d . The outer or exterior part, b , of the hook is allowed to fit snugly in contact with the part a , the upper end of the former abutting against a shoulder, e , at the back end of the tip d , and the lower end being slightly beveled and secured to the lower part of a by a rivet or screw, f ; a rivet or screw, g , also connecting the upper parts of a b near the tip d . This frame or body A of the hook may be of malleable cast-iron or other metal, and the exterior surfaces of the parts a b are rounded, while the inner surfaces, which are in contact with each other, are flat, the two parts forming a circle in their transverse section. The two parts a b , at about their center, may be connected by a rivet or steady-pin, e^x .

B, Figs. 1, 3, and 5, represents the leather covering, which is cut in suitable form and of proper dimensions to encompass the outer part, b , of the metal frame or body A and admit of being stitched together at its edges at the exterior of b , as shown at e in Figs. 1 and 5. This leather covering B is properly moistened and inserted between the two parts a b of the frame or body A , and clamped firmly in position by riveting or screwing said parts together. (See Fig. 3.) The covering is then closed snugly over the part b and its edges stitched together at e . The leather covering B extends the whole length of the part b of the frame or body A , as shown clearly in Fig. 1. The part a of the frame or body A is fully exposed, and it may be plated or galvanized with silver for the finer class of work. It will be seen that the rivets or screws f g , which secure the two parts together, pass through the leather covering B , and these rivets or screws serve to keep the covering in proper position, preventing it from shrinking from the tip d at its upper part and from the lower end of the part b .

The ordinary hook shown in Fig. 4 is simply a solid metal frame or body, C , having a tip, h , at its upper end and a plate, i , at its lower end for the screw to pass through which secures the hook to the saddle. This frame or body C is covered entirely with leather, D , with

the exception of the tip *h* and plate *i*, and the metal lining *j*, which protects the inner side of the leather, *D*, from wear or abrasion, is simply burnished over the inner surface of the leather, the lower part of *j* being secured by solder to the plate *i* and the upper part secured to the frame or body by a rivet, *k*. The upper end of the lining *j* abuts against the back end of the tip *h*.

The advantages of my mode of construction over the old are as follows:

First. There is no joint between the upper end of the lining and the tip. This joint has an unsightly appearance, and in case the upper end of the lining gets a little depressed it serves to catch the checkrein and prevent it from passing freely into the hook.

Second. The old lining is confined to a plate, which must be of sufficient thickness to admit of being bent over the leather and hold its position after being bent. Thin silver leaf cannot be employed for the purpose, and thick strips of silver would be too expensive; hence the finest hooks and terrets of this class have only a German-silver or white-metal lining. In my improvement the part *a* of the frame or body of the hook may be plated or galvanized with silver previous to the leather being applied to the hook, and a much more durable lining obtained than is necessarily used in the old hook.

Third. In my improvement, the part *b* of the frame or body of the hook only being covered, less stock is required and the leather can be more readily applied than in the old plan, and patent-leather may be used, whereas in the old mode of construction the soft pliable leather must be employed, in order to insure a smooth covering entirely around the hook.

Fourth. The leather covering in my improvement being firmly clamped between the two parts *a b* of the frame or body *A*, the leather is firmly held in position and the leather can be stretched or molded over the part *b* with the greatest facility.

Fifth. In my improvement the work when completed has a neater and more finished appearance than the old hook. A neat joint or

connection is obtained between the leather on part *b* and the metal of part *a*, and the labor of burnishing and closing or folding the lining down to the leather, which is necessary in the old mode of construction, is entirely avoided, and in case a new covering is required the part *b* may be readily detached from *a*, the old covering removed, and a new applied. This work cannot be done in the old hook without detaching and destroying the thin lining and performing the whole work over again, which would cost nearly as much as a new hook. There is another advantage attending my invention, and that is that the part *b* of the frame or body *A* may be of a metal which will not oxidize or rust, and therefore not injure the leather.

In my improvement the terrets are constructed in precisely the same way as the hooks, and they therefore do not require a separate description, the only difference being in form, the terrets being a complete circle and the hooks a portion of a circle.

Having thus described my invention, what I claim as new, and desire to secure by Letters Patent, is—

1. Having the frame or body *A* of the hook or terret formed of two parts, *a b*, connected by screws or rivets, substantially as set forth.
2. The leather covering *B*, inserted between the two parts *a b* of the frame or body *A* and fitted around the part *b*, with the rivets or screws passing through it, substantially as and for the purpose set forth.
3. The combination of the frame or body *A*, formed of two parts, *a b*, connected together, as shown, with the leather covering *B*, when the parts are so arranged that the inner part, *a*, of the frame or body will form the metal lining of the hook or terret and also the tip of the hook all in one piece without a joint, while the part *b* serves as the body for the leather covering, as set forth.

SAML. E. TOMPKINS.
